(57) **CLAIM**

The ornamental design for a footwear cleat, as shown and described.

DESCRIPTION

FIG. 1 is a bottom perspective view of a footwear cleat, showing our new design;

FIG. 2 is a bottom plan view thereof;

FIG. 3 is a top plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines portions of FIGS. 1-3 are included to show unclaimed subject matter only and form no part of the claimed design.

1 Claim, 7 Drawing Sheets
